PISTON AND CYLINDER ASSEMBLY

Floyd F. Warner, Mark L. Brooks, and Julius
E. Bardelmeier, St. Louis, Mo.

Application January 29, 1944, Serial No. 520,354

10 Claims. (Cl. 230—149)

1

This invention relates to improvements in cylinder and piston assemblies, and more particularly to improved construction, assembly, and method of operation of a piston, a cylinder in which the piston operates, and one or more abutment elements serving to seal the end zones of, or constitute a partition across the cylinder.

Expressed somewhat more concretely, an important object of the invention is attained in an assembly of cylinder, piston and gate or abutment, through which the piston passes with no appreciable loss of fluid from the cylinder or in which the gate abutment constitutes a closure.

A further important object of the invention is attained in an assembly of the type referred to in the preceding object, and in which a gate type abutment may be primarily operated by the piston incident to traversal of the abutment thereby.

An additional object of the invention is attained in the provision of a substantially continuous running seal between a gate type abutment and a piston operating through such abutment.

The foregoing and numerous other objects will more clearly appear from the following detailed description of a presently preferred embodiment of the invention, considered in connection with the accompanying drawing. Since it is to be understood that numerous variations may be made in valving provisions, details of cylinder and valve construction and arrangement, and means for lubrication of the various moving parts, the present description and claims are confined to those structural features of the invention having to do with the piston, cylinder and abutment features.

In the drawings:

Fig. 1 is a half sectional view taken in a plane including the axis of rotation of certain of the rotary elements and a center power shaft;

Fig. 2 is a sectional elevation taken in a plane normal to the axis of rotation and medially of a rotor and one of the cylinders or units of the assembly;

Figs. 3, 4, 5, 6 and 7 are diagrammatic illustrations showing, as based on the general structural arrangement of Fig. 2, but omitting details, different positions of two pistons each traversing a pair of cylinder chambers, and illustrating one mode of application of present principles to the operation of a rotary-piston type of internal combustion engine;

Fig. 8 is a diagrammatic illustration of an abutment gate-actuating cam profile, developed in a single plane for a better understanding of

2

opening and closing movements of the one or more abutment gates;

Fig. 9 is a top or plan view of a preferred form of piston, and

5 Figs. 10A, 10B, 10C, 10D, 10E and 10F represent a series of gate port openings successively attained as the abutment gate is moved from fully closed, to fully open position to permit passage of one of the pistons therethrough, this series of figures, diagrammatic in nature, similarly representing successive cross sectional contours of the leading or camming portion of one of the pistons, the locations of corresponding sections being indicated by lines A—A, B—B, 10 C—C, D—D, E—E, and F—F in Fig. 9.

15 Referring now by characters of reference to the drawing, and first to Figs. 2 through 7, two pistons are respectively numbered 1 and 2, the structure of which is hereinafter described in 20 more detail. These pistons both operate in a true circular path, and within one of a plurality of annular, or more particularly, toroidal cylinders 3.

25 Referring now to Fig. 1, the assembly may include a casing 10 provided with suitable shaft bearing portions 11 in which is operable a power shaft 12. This may, for reasons not material to the present disclosure, be of hollow form as shown. Secured to the shaft 12 against angular displacement thereon, are shown a pair of rotors 13 and 14, each characterized by a hub portion 15 which may be keyed or otherwise secured (by means not shown) to the shaft 12. The web portions of rotors 13 and 14 serve peripherally to carry the pistons 1 and 2, for which purpose, at diametrically opposite positions on each rotor web, there is provided a piston-mounting projection 16 apertured to receive a piston pin 17, this mounting being preferably but not necessarily in the nature of a pivotal mounting.

30 Just inwardly of its periphery each of the rotors 13—14 is provided with a pair of annular projections 20. As will readily appear from Fig. 1, each such projection interfits a corresponding annular recess 21 of angulate section, formed in 35 a sealing ring element 22, there being a pair of the rings 22 disposed oppositely to each other on opposite sides of each rotor periphery, and the rings 22 being retained in and supported by an annular ring-pocket block 23. The lower wall 40 of the block 23 is slotted as at 24 to permit operation in the slot, of the web of the adjacent rotor. The rings 23 coact with projections 20 in sealing relation either by resilience of the ring elements, 45 or if desired, by biasing effect of a body of fluid 55

kept under hydraulic pressure, behind one or both of the rings. For this purpose there is shown a space 25 between at least one of the rings, and the adjacent wall of the element 23. The ring retainer block structure is preferably supported by and secured to an annular block which, although obscured in Fig. 1 by certain of the abutment elements, consists preferably of a casting or like body in which are formed the toroidal cylinders. It will have appeared that, from the provision of the sealing rings 22, coaxing with the extreme peripheral portions of the rotors 13 and 14, such peripheral portions are provided with a running seal over their full perimeters, thus preventing escape in a radial inward direction of the various fluid contents of the cylinders 3 such as otherwise might occur where the piston-carrying projections or brackets 16 extend into the cylinders. Depending upon the desired application and service requirements of the assembly, any practical plurality of the cylinders 3, each containing operatively, one or more of the pistons 1 and 2, may be arranged in axial adjacency; it is now obvious that, if desired, one or more cylinders of this general type may be employed say as the cylinders of an engine of rotary piston type, while one or more additional such cylinders may be employed as pumps, compressors, superchargers and as operating accessories to the engine proper, considered as a prime mover. The description will, for brevity, be directed to a compressor piston, operable in a toroidal cylinder.

An annular cylinder or assembly thereof may be provided in diametrically opposite zones exteriorly of the cylinder proper, with a manifold or reservoir structure, two of which are shown in Fig. 2, and since these are or may be identical, although reversed in position, a description of one will suffice for both. In this construction a cell or chamber 30 is formed within an element 31 provided with external cooling fins or ribs 32, provided also with a tapped aperture 33 for the reception of a gauge or other accessory and with a pair of substantially cylindrical or even preferably tapered cylindrical valve seats 34 and 35, for the operative reception respectively, of rotary valves 36 and 37. Each of the valves contains a transverse fluid passage 38, and the structure just described may be conveniently mounted on the cylinder block structure, as by bolts or screws 40. Although it may be noted as preferable to actuate the valves 36 and 37 with a quick oscillating motion, and to operate valve 37 entirely after full opening and full closing of valve 36, the specific, preferred means of valve actuation being the subject of a contemplated application for patent on this feature per se, need not be further described herein.

It is a preference to utilize the described pair of pistons 1 and 2 operating continuously in such manner that each fully traverses the entire annular space or two half-annular chambers, of each cylinder 3. With this arrangement there is preferably provided a pair of abutments generally indicated in Fig. 2 at 45 and 46. In preferred form each abutment consists of a reciprocally actuated, slidably movable gate, the gate element proper of which is indicated at 47 (Fig. 1) and which is arranged to reciprocate from the position shown by dotted lines in Fig. 1, downwardly in that figure to the full-open position shown by full lines but in section.

As will appear, actuation of each of the gates 47 is effected primarily by the pistons in passing

therethrough, although for the purpose of initiating the movement of the gate barely in advance of each piston reaching the gate, there is preferably employed a cam arrangement (later described) serving to effect the movement of element 47 downwardly (Fig. 1), return thereof to its initial or closed position being effected by a gate return spring or plurality thereof 50, provided with an enclosing housing 51 of cylindrical form, this housing being in turn reciprocally movable within a stationary holder 52. A plurality of the spring and housing assemblies may, if desired be employed for each gate.

As a means tending to bias the lower margin 15 53 of the gate, into close sealing engagement with the upper margins of the sealing rings 22, and similarly with the upper margins of the ring carriers 23, there are utilized a plurality of coil springs 54 which are kept under some moderate 20 loading between the innermost margins of the elements 31 and the upper or outer margin 55 of the slidably gate member 47.

Proceeding now to a description of the gate-actuating cam means, a preferred embodiment 25 thereof includes a plate or disc generally indicated at 60, which is carried by and securely assembled to the shaft 12 as by a key or any other suitable locking means (not shown) so that the cam plate operates in assured and fixed timed 30 relation with the rotors such as 13 and 14, and hence in a definitely timed relation to the pistons.

Mounted so as to project substantially at a 35 right angle to the disc 60, is a cam element 61. For reasons of effecting a precision adjustment of the cam 61 with respect to the disc 60, the cam is preferably formed as a separate element and secured to the disc as by a plurality of screws, of which one is shown at 62. The screw-receiving 40 apertures in plate 60 may, if desired, be somewhat enlarged to permit some moderate degree of angular adjustment of the cam 61 with respect to cam plate 60. It will have appeared that the movable gate element proper 47 of the abutment assembly, is somewhat undercut in the region of its innermost right hand margin as indicated at 63, whereby portion 63 serves, in effect, as a follower for cam 61. It will be understood that, although a single cam assembly is 45 described, the requisite plurality, corresponding to number of gate elements, will be utilized.

A preferred design of profile of cam 61 will 50 hereinafter be more particularly described, since it will be better understood following a discussion of the structure of pistons 1 and 2. As heretofore noted, the pistons constitute, by preference, the primary gate-actuating agencies, and in effect themselves serve as gate-operating cams so as to supplement the operating influence of 55 cam 61, all as will later more clearly appear.

It will have been noted from Fig. 1 that the gate 47 is ported to enable passage through the gate, of the several pistons in each of the cylinders 3 controlled by the given abutment gate.

60 These ports are indicated in dotted lines at 65 (Fig. 1), and by preference, are circular and each of an area corresponding to the transverse sectional areas of each of the cylinders 3. It will 65 now have become obvious that, as the gate element 47 is slidably shifted in an opening direction (Fig. 1), an initial effect will be to create a very minor, merely pin-hole opening adjacent the side wall of each cylinder. This opening is 70 of a shape approximating that of the overlapping 75 area of two partly superposed circular elements,

and the extent or area of such opening will be increased until it becomes fully circular. This occurs when the gate reaches full-open position, and its circular port becomes fully coincident with the cross section of the cylinder. Closing movement of the gate will obviously result in a reverse sequence of openings of gradually reducing area until nearly or completely full closure of the gate takes place. A diagrammatic showing of the forms of six such successively attained piston-openings in the gate, will be seen in Fig. 10A and those following, it being noted that these correspond closely to successive sectional shapes of the fore end or nose of the piston, hereinafter described.

Proceeding now to a description of the pistons 1 and 2, each thereof, as will appear from Figs. 2 and 9, is of what may be termed a horn shape; since the shaping and construction of the two pistons may be identical, a description of piston 1 will suffice for both. Each piston is preferably formed on a longitudinal axis which is arcuate, or substantially so, the arc thereof being drawn on a center which approximates the axis of rotation of the rotor 13 or 14 by which the piston is carried. The rearmost or trailing one-third or so of the piston, indicated generally at 70, is or may be close to cylindrical form, departing from a true cylindrical form only by reason of being formed on an arcuate longitudinal axis. The leading two-thirds or so, being the nose of the piston, indicated at 71, is characterized by an apex portion 72, and is of a gradually increasing cross section rearwardly of the apex back to the trailing portion 70. Successive cross sections of piston portion 71 may be described as derived from successively larger overlapped areas of two circles each of the same diameter as the cylinder bore, the successively larger cross sections corresponding to the superposed parts as such circles are successively brought into increasingly overlapped relation. From the description just given, and from Figs. 10A, 10B, 10C, 10D, 10E and 10F, it will appear that the top and bottom of leading portion 71 are each drawn somewhat to an edge, and that the opposite lateral surfaces of leading piston portion 71 are each formed substantially on a true arc, but with the centers of such arcs distinctly out of coincidence.

It should further be noted that, in the example disclosed, apex 72 is neither located in nor travels along a median of the cylinder, but lies close to the side thereof identified with the first opening of the gate element 47. From this fact results the skewed or canted aspect of the piston when viewed in plan, as will appear from Fig. 9.

It is a preference not to attempt any packing provisions for the leading portion 71 of the piston, but is a distinct preference to provide the trailing portion 70 with a series of ring grooves, each for the reception of a piston ring or like packing element 73.

While for simplicity of abutment structure each abutment is shown as utilizing but a single reciprocable, ported gate element, it should be noted that the gate shown may be duplicated in each abutment assembly, with the two gates in adjacency, each provided with an individual camming assembly and with the ports of the two gate elements arranged to approach, first partly overlap, then be brought into register to pass the piston. Although requiring twice the number of gates otherwise necessary, and additional cams, an advantage is presented by the double gate arrangement in that the apex of the piston may

be disposed centrally thereof, with some simplification of piston production, and the gate opening thus initiated in a region in or near the axis of the cylinder.

The operations of cam 61 and of piston 1, for example in effecting an opening movement of the gate element 47, are thought to have been made apparent from the description of parts and their relation, but it may be noted for completeness, as a preference, to initiate the opening movement of the gate slightly in advance (say only one or two degrees) of actual attainment of gate position by the apex 72 of the piston. This effect is, now obviously, attained by precision timing of cam 61, such that the gate will have barely opened no more than to provide a sufficient starting aperture for entrance of the apex 72 of the piston. This effect, attained by cam profile, will best be seen from the diagram of Fig. 8 wherein there is shown as a planar development, the leading margin of the cam lobe and indicated at 80, a toe portion which serves to effect such an initial gate opening. At this point the piston takes over the gate opening movement, and thereafter, and until the piston has completely passed through the port of the gate, the piston serves as the gate-actuating agency in conjunction with the cam, with the now obvious advantage that there is thus assured a running seal between the margin of the port 65 in the gate, and the periphery of the piston portions 71 and 70 in this sequence. It may be desirable, although not in all cases strictly necessary, that the margins of the ports 65 of the gate be somewhat flared or tapered to enhance the area of wiping engagement of the gate port margins with the periphery of the piston portion 71. It will now be observed from the cam profile of Fig. 8, that, as soon as the piston has attained such a position that its trailing portion of circular section reaches the port 65 of the gate, no further gate opening takes place, but that the piston remains nonetheless closely embraced by the port margin and adjacent coacting portion of the cylinder wall, so as to perfect the fluid seal in this end zone of the cylinder. A further study of the cam profile of Fig. 8 will reveal a further desirable feature namely, the provision of the gradual downward trailing slope indicated at 81 of the camming contour of the cam lobe.

It should here be noted that, during cam movement such that the gate is actuated by the toe 80 of the cam lobe, and again during that portion in which the heel of the lobe shown at 81, is engaged by the gate under the influence of spring 50, the gate is entirely cam-controlled by member 61, but that, during all intervening time being through the angle shown as 67½ degrees in Fig. 8, the gate is primarily or solely under control of the piston. Although a cam contour is provided between portions 80 and 81 such as to effect substantially the same gate opening movement as results from the piston, the cam profile or lobe nevertheless bears a slightly trailing relation, or otherwise expressed, a slightly spaced relation, with respect to the cam following portion 63 of the gate.

In the showing of Fig. 1, embodying two axially aligned cylinders, they may be employed for differing purposes, or both as compressor cylinders, acting separately or as successive stages. Where only two cylinders are employed in adjacency, the disclosed arrangement can best be timed within itself and balanced by angularly displacing the pistons within one cylinder, 90

degrees from corresponding pistons of the companion cylinder, in which case the abutment assemblies including the gates, will obviously be 90 degrees displaced in the two cylinders, thus requiring a separate cam plate, cams, etc., with gates individual to the associated cylinder, but without departing from the major elements and features described.

When it is considered that under certain conditions at least one of the pistons is subject to a maximum fluid pressure substantially at the time when it must traverse the gate, the advantage, now evident, of being able to maintain the end of the cylinder substantially completely sealed while permitting passage of the piston therebeyond, cannot be over-estimated. This advantage particularly evident in and most importantly adapted to a rotating piston type of structure in distinction from the so-called oscillating piston types of compressor.

The operation of the present structure is best seen by reference to a simplified construction in which is utilized only a single cell or chamber such as 30, for example, the one at the left hand side of Fig. 2. Such chamber is equipped with a self-opening, spring-loaded intake valve (not shown), opening inwardly of chamber 30, and an outwardly opening spring-loaded discharge valve (not shown), controlling a port out of the chamber 30. These valves are not shown since they are or may be of conventional poppet type. Let it be further assumed that a single gate or abutment assembly such as 45 is employed, with a single piston 1 and a cylinder 3 in the form of a full torus, omitting the right hand cell 30 and adjacent valves. In such a simplified construction, piston 1 will, in the position shown, be compressing and displacing fluid through the upper valve 36 to the cell 30, thence outwardly thereof through the poppet discharge valve. As piston 1 approaches the gate 45 the upper valve 36 is closed, and the lower rotary valve 37 is opened. Piston 1 after traversing the gate, now draws a fresh charge through the intake poppet valve via chamber 30 and through the lower rotary valve 37. While thus inducing a fresh charge of air, the piston is compressing some air ahead of itself, and as it again approaches the gate, valve 36 is opened and 37 is closed. At this time, the poppet discharge valve may open, depending upon its spring loading, but as the piston again traverses the abutment, valve 37 remaining closed, and valve 36 again reopens. Thus the piston displaces ahead of itself virtually a full cylinder of fluid which is driven outwardly through valve 36, chamber or cell 30, and therefrom through the spring loaded discharge valve.

It will have appeared that the duplication of the structure described as in Fig. 2, will result in an operation quite similar to that described, except with shortened stroke and more frequent discharge pulsations. Obviously, if desired, the plurality of cylinder assemblies, for example as shown by Fig. 2, may be used for increased capacity, or may be used for consecutive cycles of displacement as in multi-stage operation.

It will now appear that the arrangement identified with the improved piston, cylinder and abutment gate of the present design, serve fully to attain each and all of the several objects hereinabove expressed, as well as many others implied from the more detailed description of parts and assembly.

Although the invention has been described by making particularized reference to a selected

embodiment of the invention, the detail of description is to be understood solely in an instructive rather than in a limiting sense, numerous variants being possible within the scope of the claims hereunto appended.

We claim as our invention:

1. A piston adapted for use in a toroidal cylinder and in traversing relation to a wiping and sealing piston-gate structure, the piston being characterized by a body portion and a nose portion, the nose portion being substantially apexed at its forward or leading end, and being formed rearwardly of its forward end to present a series of transverse cross sections each of which exhibits a major axis and a minor axis of substantial symmetry, with one of said axes terminating in defined, substantially rectilinear and longitudinal edge portions.

2. A piston adapted for use in a toroidal cylinder and in traversing relation to a wiping and sealing piston-gate structure, the piston including a body portion and a nose portion, the nose portion being provided with a substantially pointed leading end and rearwardly of its leading end, being characterized by convex, substantially regularly curved sides, and presenting a series of cross sections each exhibiting a major and a minor axis of symmetry, the convex sides of the nose portion being drawn on centers each lying substantially on a minor axis of symmetry, and the convex sides intersecting to form substantially linear, angulate, rib-like protuberances.

3. In a piston adapted for use in a toroidal cylinder and in traversing relation to a wiping and sealing piston-gate structure, the piston including a body portion and a nose portion, the body portion being substantially cylindrical and the nose portion being characterized by convex opposite sides so related as to result in a series of increasing transverse sections, from leading end to a zone approaching the body, which sections are of double convex aspect, the convex sides intersecting to form pronounced linear, substantially longitudinal apices extending from the leading end of the nose portion rearwardly substantially to the body.

4. A piston adapted for use in a toroidal cylinder and in conjunction with a wiping and sealing abutment adapted to be traversed by the piston, the piston including a body portion and a nose portion, the nose portion being of a generally horn-shape, and constructed to present a series of cross sections increasing in area from the leading end of the nose portion to a zone near the body portion, each such cross section exhibiting a major axis and a minor axis of symmetry, and the sides of the portions of the nose including the said sections, intersecting along opposite margins of the nose in a manner to form in such zones of intersection, substantially sharp and substantially linear ridge portions.

5. In a piston of a type for use in a toroidal cylinder and in cooperative relation with a wiping and sealing abutment structure traversed by the piston, a body portion and a nose portion, the nose portion having an attenuated leading end, and rearwardly thereof being characterized by a series of transverse sections each of double convex aspect and increasing in both depth and width from a zone near the leading end of the nose, to a zone near the body of the piston, the nose being thus provided with distinct angulate ridges along its top and bottom surfaces, the body being of substantially circular cross sections rearwardly of the nose portion.

6. In a piston adapted for use in a toroidal cylinder and in cooperative relation with a wiping and sealing piston abutment structure arranged to be traversed by the piston, the piston including a substantially cylindrical body and a nose of a generally horn shape pointed at its leading end, the nose being characterized by a series of transverse sections each increasing in area rearwardly of the nose and each conforming in area and shape to an overlapped area of partly overlapping circles, the nose portion thereby being formed to present a pair of longitudinal, substantially linear, angular protuberances along its opposite sides.

7. A piston adapted for use in a toroidal cylinder and in conjunction with a wiping and sealing piston-gate structure through which the piston is to pass, the piston including a body portion of substantially cylindrical shape, and a long nose portion substantially apiced at its forward or leading end, the nose being convex on its opposite sides but of lesser width than the body whereby it presents a relatively laterally flattened aspect, the convex sides of the nose portion sharply intersecting each other along opposite margins of the nose, to result in substantially rectilinear, protuberances of an angular section along opposite portions of the nose, said protuberances merging into the body in a zone of juncture of the body and the nose.

8. A piston adapted for use in a toroidal cylinder, and in conjunction with a wiping and sealing piston-gate structure to be traversed by the piston, the piston including a body of substantially cylindrical formation and a nose substantially pointed at its leading end, the nose being of sub-

and relatively sharp protuberance along each of two opposite portions of the nose and extending substantially from the pointed leading end of the nose back to the body, the nose being formed on an axis curved on substantially the same center as the toroidal cylinder in which the piston is to be used, the said axis of the nose being angularly related to the axis of the piston body in such manner that one side of the nose and one side of the body both lie substantially tangent to a common plane, and so formed that the apiced end of the nose lies substantially in said plane of tangency.

10. In a piston and cylinder assembly adapted for use as a compressor, a toroidal cylinder, a valved transfer chamber external to but communicating with the toroidal cylinder, and provided with a pair of passages from the chamber to said cylinder, a valve in each of said passages, a piston-wiping and sealing gate structure or abutment located to extend across the toroidal cylinder between the said passages, and a piston operating in the cylinder and in traversing relation to said wiping and sealing piston gate structure, the piston being characterized by a body portion and a nose portion, the nose portion being substantially apiced at its forward or leading end, and being formed rearwardly of its forward end to present a series of transverse cross sections, each of which exhibits a major axis and a minor axis of substantial symmetry, with one of said axes terminating in defined, substantially rectilinear and longitudinal edge portions, the piston gate structure including cooperating elements adapted to define a port for the piston which port is of variable shape and area as traversed by the
